UNITED STATES PATENT OFFICE.

CHARLES A. PRINDLE, OF CHICAGO, ILLINOIS.

CHAIN OR THE LIKE.

1,184,260.

Specification of Letters Patent.

Patented May 23, 1916.

Application filed April 21, 1913. Serial No. 762,577.

To all whom it may concern:

Be it known that I, CHARLES A. PRINDLE, a citizen of the United States, residing at Chicago, in the county of Cook and State 5 of Illinois, have invented certain new and useful Improvements in Chains or the like, of which the following is a description.

My invention belongs to that general class 10 of devices known as chains, and relates particularly to chains for transmitting power or motion, and is in the nature of an improvement over the chain illustrated in my United States Letters Patent No. 1,058,260, dated April 8, 1913.

15 The invention has among its objects the production of an improved chain of the kind described that is simple, convenient, durable, efficient, and satisfactory, that may be manufactured at comparatively small cost and 20 used wherever found applicable.

To this end my invention consists in the novel construction, arrangement and combination of parts herein shown and described, and more particularly pointed out 25 in the claims.

In the drawings, wherein like reference 30 characters indicate like or corresponding parts, Figure 1 is a plan view, a part being shown in section, of several assembled links. Fig. 2 is a side elevation of the same. Fig. 3 is a perspective view of the locking plate 12. Fig. 4 is an enlarged view of the socket end of the link before the adjacent link is seated and the plate positioned. Fig. 35 5 is a sectional view substantially on line 5, 5 of Fig. 4, the adjacent link seated and plate positioned and secured in place. Fig. 6 is substantially a sectional view taken on line 6, 6 of Fig. 5. Fig. 7 is a similar view, 40 illustrating the removal of the adjacent link. Fig. 8 is a plan view of the socket end of a link, illustrating the modified construction, and Fig. 9 is substantially a sectional view on line 9, 9 of Fig. 8.

45 Referring to the drawings, the links shown are substantially similar to that illustrated in my patent previously mentioned, preferably modified to embody the improvement herein set forth. To assemble or dis- 50 assemble the links shown in the patent mentioned, it is necessary to move the links so that one would overlie the other, and then substantially move it transversely or laterally, so that the links are not easily detached

when in use. In the present application I 55 have illustrated similarly formed links in all the figures, but it may be mentioned that the links may be modified to a considerable extent, as they are substantially locked in position and prevented from becoming detached, even if they were made so that it would be unnecessary for tilting or laterally moving the links to attach or detach them.

Each link comprises a shank or body- 60 part 1, provided with an enlargement 2 at one end, and with a socket or cup-shaped end 3 at the opposite end. The socket end 3 is preferably made substantially spherical, or formed so as to give a symmetrical and 70 attractive appearance, and to avoid sharp corners to catch in or pick up the foreign objects. The socket end is provided with a socket or recess 4, and with an opening 5 adjacent to the body or shank of the link, to admit the enlarged end of an adjacent 75 similarly formed link. The socket end is also preferably slotted from the opening 5 toward and past the extremity of the longitudinal axis of the link, for the passage or 80 reception of the body or shank of the adjacent link when assembled.

A plate, clip, or the equivalent 12, is provided for each link to close the opening 5 in the socket when the links are assembled, 85 the same forming substantially a closure. The same is made of suitable shape and material, and maintained in position in any desired manner. A very convenient method of attaching the plates or closures is to form 90 the socket ends 3 with flat shoulders 9, 9 (see Fig. 4) and with ears or lugs 10, 10. An opening 11 is preferably provided in the socket at the shank. The plate is provided with ends 14, 14 adapted to rest upon the 95 flat shoulders 9, 9, and with a tongue 15 adapted to fit into the opening or recess 11. The plate may also be provided with a short tongue 13 adapted to extend slightly into the slot 6. After the enlarged end of one 100 link has been inserted in the socket of an adjacent link, the plate 12 is positioned with the tongue 15 in the recess 11, and the ends 14 proximate the ears 10. A slight blow or 105 tap of a hammer, or other tool, on each ear 10, is sufficient to slightly bend down the ears 10, 10, or offset the socket to overlie the ends or corners 14, securely locking the

plate in place. In Fig. 5 the ears 10 before tapping are indicated in dotted lines. The tongue 13 prevents any lateral movement of the plate. It will be noted, as most clearly shown in Fig. 5, that the plate is slightly raised or bent at 16 so as to substantially form a slight spring action or give resiliency, and also form a symmetrical or pleasing design. In case it is desired to remove any of the links, the plates may easily be detached by inserting a tool, as for example, a cold chisel, under the lugs 10, and raising the same.

In the construction shown in Figs. 8 and 9, a slightly modified construction is shown, in which the plate 18 is rounded and provided with tongues 21, or corners, which fit in recesses 22, and are maintained in position by the lugs or ears 23 on the socket. The plate is provided with a tongue 20, which fits in the recess 11. Where the plate 18 is of some thickness, and therefore may not easily be bent or spring into position, the lugs 23 may be left turned up, that is, the link may be so constructed and turned down after the plate is positioned. If the plate is made substantially thin, as indicated by the dotted lines 19, so that it is similar to the other plates previously described, the slots or grooves 22 may be formed in the link, and the plates sprung into position, their resiliency maintaining them in place.

It is, of course, understood that the links may be of any desired proportions, and of any suitable material, the proportions and material depending upon the use for which the chain is intended. The uses for chains constructed as described are many, but it may be stated that they are particularly desirable for use on agricultural machinery, vehicles, conveyers, hoisting machinery, or block and tackle. As was previously set forth, the links need not be constructed exactly as set forth in my patent mentioned, as the plate at each socket securely locks all the links together so that they cannot be detached or become accidentally separated, except by the intentional removal of the plates.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:—

1. A link formed at one end with an enlargement, and at the opposite end with a socket having an opening adjacent the body of the link to admit the enlarged end of an adjacent similarly formed link, and slotted from the opening toward and past the extremity of the longitudinal axis of the link

for passage of the body of the adjacent link, and a detachable plate arranged over said opening, said plate underlying a portion of the link at said socket end and provided with a tongue projecting into the slot at said end. 70

2. A link formed with an enlargement at one end, and with a socket at the opposite end, having an opening adjacent the body of the link to admit the enlarged end of an adjacent similarly formed link, and slotted from the opening toward and past the extremity of the longitudinal axis of the link for passage of the body of the adjacent link, and a plate detachably secured to said socket end at said opening, said plate slightly projecting into said slot whereby lateral movement of the plate relative to the link is prevented. 80

3. A link formed with an enlargement at one end, and with a socket at the opposite end, having an opening adjacent the body of the link to admit the enlarged end of an adjacent similarly formed link, and slotted from the opening toward and past the extremity of the longitudinal axis of the link for passage of the body of the adjacent link, a suitably formed plate, and means for securing said plate at said socket end opening, comprising overlying lugs on said link end, said plate provided with tongues on opposite sides thereof, one tongue projecting into the slot between said lugs and the other engaging the link at the side of the opening opposite said lugs. 95

4. A link formed with an enlargement at one end, and with a socket at the opposite end having an opening to admit the enlarged end of an adjacent similarly formed link, and slotted from the opening toward and past the extremity of the longitudinal axis of the link, for passage of the shank of the adjacent link, said socket end provided with a recess and with lugs proximate the opening, and a suitably formed plate provided with a tongue for engagement with the link in said recess, and formed to underlie said lugs. 100

5. In a device of the kind described and in combination, a link formed with an enlargement at one end, and with a socket at the opposite end having an opening to admit the enlarged end of a similarly formed adjacent link, and slotted from the opening toward and past the extremity of the longitudinal axis of the link, for passage of the shank of the adjacent link, said socket end provided with a recess and with lugs proximate the opening, and a suitably formed resilient plate provided with a tongue for engagement with the link in said recess, and formed to underlie said lugs. 115

6. In a chain, a link formed at one end with a socket having an opening adjacent the body of the link to admit the co-operating end of an adjacent link, and slotted from 120

the opening toward and past the extremity of the longitudinal axis of the link for the passage of the adjacent link, said link having a shoulder at said opening on each side 5 of the slot and a recess at the side of the opening opposite the slot, a plate mounted on the link at said end and corresponding in contour to the exterior of the link about said opening, said plate projecting into said

recess, and means for securing the plate on 10 said shoulders.

In testimony whereof, I have hereunto signed my name in the presence of two subscribing witnesses.

CHARLES A. PRINDLE.
